Primary Examiner—Celia Murphy

(74) Attorney, Agent, or Firm—Milbank, Tweed, Hadley & McCloy LLP

(57) **CLAIM**

The ornamental design for a shoe sole, as shown and described.

DESCRIPTION

FIG. 1 is a perspective view of a shoe sole showing my new design;

FIG. 2 is a bottom plan view thereof;

FIG. 3 is a right side elevational view thereof;

FIG. 4 is a left side elevational view thereof;

FIG. 5 is a front elevational view thereof; the top surface not forming any part of the claimed design; and,

FIG. 6 is a rear elevational view thereof.
